CHARLES E. WILCOX, OF EAST BAKERSFIELD, CALIFORNIA, ASSIGNOR, BY DIRECT AND MESNE ASSIGNMENTS, OF ONE-THIRD TO HIMSELF, AND ONE-THIRD TO WILLIAM G. KNAPP, OF ALHAMBRA, CALIFORNIA, AND ONE-THIRD TO OIL WELL SUPPLY COMPANY, OF PITTSBURGH, PENNSYLVANIA, A CORPORATION OF PENNSYLVANIA.

WELL-BORING APPARATUS.

1,235,866.

Specification of Letters Patent.

Patented Aug. 7, 1917.

Application filed August 1, 1913. Serial No. 782,492.

To all whom it may concern:

Be it known that I, CHARLES E. WILCOX, a citizen of the United States, residing at East Bakersfield, in the county of Kern and State of California, have invented new and useful Improvements in Well-Boring Apparatus, of which the following is a specification.

The invention disclosed herein was divided, and a divisional application, Serial No. 46,191, was filed by me on August 18, 1915.

This invention relates to well boring apparatus and more particularly to rotary well boring apparatus, in which the boring string carrying the boring tool or device is rotated in the well hole in producing the well hole, by suitable means located at the mouth of the hole.

The invention relates more specifically to the swivels and means of suspension of same, whereby the boring string is suspended in the well hole, by suitable means extending therefrom to the derrick or rig.

The invention has for its object to provide improvements in well boring apparatus of the character stated in which the swivel and suspension means are so organized that the suspension means may be utilized for handling the joints or sections of the boring string and the casing when the swivel features *per se* are not in use.

In practising the invention, the swivel is applied to the boring string at the top of the same and it coöperates with the collar at the top of the string in holding up the string.

Ordinarily swivels of rotary well boring apparatus are provided with swivel stems which are concealed within the string, extending downward to and being jointed to the string beneath the swivel.

In accordance with the invention the swivel is applied directly to the top joint of the string and beneath the collar at the top of said top joint. The improved swivel and suspension means are so jointly organized that the features which pertain strictly to the performance of swivel functions may be removed from the suspension means features, enabling the suspension means to be

used as an elevator in holding up and handling the joints of the strings and casings.

To more perfectly adapt the suspension means for its performance as such an elevator, certain elevator parts are applied to the suspension means in substitution for the parts and features which are applied to the suspension means to complete the swivel. Thus the suspension means may be converted from a swivel into an elevator and from elevator to swivel, thus to adapt it for the particular class of use and service demanded of it in carrying on the boring operations and in the general development of the well hole.

The invention has for further objects the provision of improved well boring apparatus of the general character stated which will be of relative superiority and inexpensive of construction originally, combined with positiveness in operation, convenience in handling and control and durability and the use of which will be attended by an appreciable saving of time and a general increase of efficiency and serviceability.

With the above and other objects in view the invention consists of the novel and useful provision, construction, inter-relation, combination and relative arrangement of parts, members and features, all as herein-after described, shown in the drawings and finally pointed out in claims.

In the drawing:

Figure 1 is a central vertical sectional view partly in elevation, of a portion of certain features of well boring apparatus organized to embody the invention;

Fig. 2 is a transverse view or section of the same taken on the line x^2-x^2 , Fig. 1, and looking in the direction of the appended arrows.

Referring with particularity to the drawing A therein designates generally the suspension means organized for use as a swivel in connection with the boring string of which the upper joint or section is shown in the drawing. C denotes generally the suspension means organized as an elevator for handling the casing D or the string B the upper joint or section of the casing being shown in the drawing. The suspension

means is provided with the usual bail E which is in turn suspended in the rig or derrick in the usual manner. Circulation means F are applied to the boring string B 5 at the top of the same.

The suspension means A comprises in the main an annular frame or ring 7, with which the bail E is pivotally connected, at diametrically opposite points as at 8. The annulus 10 7 is thickened at its lower portion to produce an annular inner shoulder 8^a. The swivel members or features are applied to the shoulder 8^a of the annulus 7 and to an annular plug 9, screwed into the lower portion 15 of the annulus 7, as at 10, flush with the shoulder 8^a. The annulus 7 has an inner diameter large enough to pass the collars of any joints or sections of the boring string or casing with which the suspension 20 means is to be used. Resting upon the plug 9 and shoulder 8^a is an annular ball race carrier 11, having spaced upstanding annular side walls 12 and 13 between which are fitted upper and lower annular ball race 25 plates 14 and 15 respectively. A series of ball bearings 16 is accommodated between the ball races which are grooved or channeled to receive the same. The ball race plate 14 fits into a shallow groove, as at 17, 30 in an annular cap or crown ring 18 which is provided with a depending annular internal extension 19 spaced from the ball race carrier inner wall 12 and inward of same. An annular packing ring 20 is disposed 35 between the top of the wall 12 and a channel in the crown ring 18. A series of hooks 21 extend from top of the carrier wall 13 into an annular channel 22 in the periphery of the crown ring 18 beneath an overhanging 40 annular ledge 22^a which overlies the top of the annulus 7. Coöperating with the crown ring 18, and fitting between the same and the annular inner extension 19 of the same and the boring string B, is a split bushing 45 23 which is provided with an outwardly extended top flange 24 which is engaged with and beneath the collar 25 at the top of the boring string and whereby the boring string is connected with the fluid circulating means 50 F. With the parts inter-related as just described the weight of the boring string is imparted to the suspension means A through the annulus 7 and its shoulder 8^a and the annular plug 9. When rotation is imparted 55 to the string B, by the usual rotary table or any suitable means the crown ring 18 and ball race plate 14 rotate with the string, and with relation to the ball race plate 15 and the ball race carrier 11. When, now, it is 60 desired to use in one manner the suspension means E for the purpose for which the usual elevator is employed the boring string may be held up by slips or otherwise, and the suspension means and the elevator features 65 e lowered until the split bushing 23 is free

to be removed from its working position, when the suspension means may be lowered beneath the next lower collar and the split bushing again be put into place, and the suspension means elevated, thus further elevating the boring string. This operation may be performed in breaking up the boring string and the reverse of this operation may be performed in making up the boring 70 string. 75

The annulus or body 7 of the suspension means is made large enough so it may be utilized as part of an elevator for casing of maximum diameter and the swivel features a and the elevator features c are of such 80 dimensions under any certain conditions, as to bridge the space between the boring string or casing and the body. The liquid circulation means F comprises a tubular body 31 which screws into the top collar 25 upon 85 the boring string, and within which is fitted an upper packing ring 32 and a lower packing ring 33 separated by a compression spring 34 forcing the lower packing ring 33 against a seat 35 at the lower end of the 90 body 31, and forcing the upper packing ring against the gland 36, which with its head 37, is split vertically and transversely the two parts thereof being bolted together as at 38, and the head thereof being bolted to the body 31, as at 39, to bring the gland down against upper packing ring 32. The wash pipe or feed pipe of the circular means 95 F is rotatably received within the body 31 and the packing rings 32 and 33, which are 100 disposed between such body and such pipe, the lower end of the pipe extending beneath body 31, to discharge fluid into the top section of the boring string. An integral flange 42, upon the pipe 40 within the gland 105 head 37, is disposed between two bearing rings 43 and 44, accommodated within the gland head 37, thus constituting the thrust bearings preventing vertical displacement of the pipe 40. 110

As the boring string rotates it carries with it the body 31 and connected parts, but the wash pipe or feed pipe 40 remains stationary, being held against frictional drag by a supply pipe or pipes 45 connected with 115 nipples 46 at the ends of a header or coupling at top of pipe 40.

I do not desire that the invention be so interpreted as to limit it to any particular and specific features and details of construction and combination and inter-relation herein specified and expressed further than is required by a fair interpretation of the following claims; as many wide variations may be made in these respects in perfecting 120 the invention. 125

Having thus described my invention I claim and desire to secure by Letters Patent:

1. In apparatus of the character disclosed, suspension means, comprising a frame and 130

a suspending device therefor, and swivel means applied to the frame and comprising a ball race carrier, ball race plates and balls in the carrier, and a crown member fitting 5 over the ball race plates; there being means of connection between the crown member and the ball race carrier whereby they may be jointly removed from the frame.

2. In apparatus of the character disclosed, 10 in combination with a boring string; suspension means for the string, and swivel means coöperating with the suspension means and with the string at the top thereof to support the string; a split bushing being 15 provided between the swivel means and the string.

3. In apparatus of the character disclosed, suspension means, comprising a frame and a suspending device therefor, and swivel 20 means detachably applied to the frame and adapted to coöperate with a boring string to rotatably suspend the same; a split bushing being provided for insertion between the swivel means and the string.

25 4. In apparatus of the character disclosed, suspension means, comprising a frame and a suspending device therefor; and swivel means comprising two relatively rotatable members applicable respectively to said frame and to a boring string; said frame being annular and having an inwardly projecting shoulder upon which said swivel means rests, and a plug screwed into said frame flush with said shoulder.

35 5. In an apparatus of the character disclosed, in combination with a boring string having an external thread formed on the upper end thereof, a standard pipe collar secured on said thread and having its upper 40 end interiorly threaded to receive an additional joint of the boring string, a support, and swivel means carried by the support, said swivel means resting against and supporting said collar.

45 6. In an apparatus of the character disclosed, in combination with a boring string

having an external thread formed on the upper end thereof, a standard pipe collar secured on said thread and having its upper 50 end interiorly threaded to receive an additional joint of the boring string, a support, swivel means carried by said support having an opening therein through which said collar can pass, and means by which said collar may be supported on said swivel means. 55

7. In an apparatus of the character disclosed, in combination with a boring string having an external thread formed on the upper end thereof, a standard pipe collar secured on said thread and having its upper 60 end interiorly threaded to receive an additional joint of the boring string, a support, swivel means carried by said support having an opening therein through which said collar can pass, and a split bushing adapted to 65 be slipped in said opening in said swivel means, said split bushing being so shaped that it is supported by said swivel means.

8. In an apparatus of the character disclosed, in combination with a boring string 70 having a collar thereon, a support, swivel means carried by said support and having an opening therein through which said collar may pass, and means for supporting said collar on said swivel means. 75

9. In an apparatus of the character disclosed, in combination with a boring string having a collar thereon, a support, swivel 80 means carried by said support and having an opening therein through which said collar may pass, and a split bushing adapted to be placed in said opening about said boring string, said split bushing being so placed that it is supported by said swivel means and supports said collar. 85

In testimony whereof, I have signed my name to this specification in the presence of two subscribing witnesses.

CHARLES E. WILCOX.
